(57) **CLAIM**

The ornamental design for a ball storage rack as shown and described.

DESCRIPTION

FIG. 1 is a perspective view of a ball storage rack showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of area 9 shown in FIG. 1; and, FIG. 10 is an enlarged view of area 10 shown in FIG. 1.

The broken lines depict portions of the ball storage rack that form no part of the claimed design. The dash dot dash lines in FIGS. 1, 9 and 10 are for the purpose of depicting the boundary lines of the enlarged view and form no part of the claimed design.

1 Claim, 10 Drawing Sheets(56)
